UNITED STATES PATENT OFFICE.

EDWARD C. ALBREE, OF SWAMPSMOTT, MASSACHUSETTS, ASSIGNOR TO ALBREE SELF FIGURING SYSTEM COMPANY, OF BOSTON, MASSACHUSETTS, A CORPORATION OF MASSACHUSETTS.

ACCOUNTING SYSTEM.

1,019,290.

Specification of Letters Patent.

Patented Mar. 5, 1912.

Application filed January 11, 1908. Serial No. 410,333.

To all whom it may concern:

Be it known that I, EDWARD C. ALBREE, a citizen of the United States, residing at Swampscott, county of Essex, State of Massachusetts, have invented a certain new and useful Improvement in Accounting Systems, of which the following is a specification, reference being had therein to the accompanying drawings.

10 My invention has for its object an accounting system particularly adapted for keeping a record of the time worked by the laborers on jobs upon which the laborers work irregularly or are present only for portions of 15 the day. Such a case is that of stevedores who begin work when a vessel arrives and stop when the vessel is loaded.

My invention provides an easy and simple 20 means of keeping track of the time worked by the men and the amount earned by them without the necessity of any figuring.

The invention involves the use of cards 25 provided with sets of numerals which for convenience may be denominated subtrahend numerals, minuend numerals and product numerals, these last being the difference between certain numerals of the first two sets multiplied by a constant which is the wage 30 per hour. These cards are punched at the time when the workman begins work and at the time when he leaves and become his voucher for the work which he has done. If desired, the cards may be made in sets or pairs, one of the cards bearing the subtrahend 35 and minuend numerals, the other of said cards bearing the product numerals; or all of the numerals may be put on both cards employing, if desired, the front and back faces.

40 The invention will be fully understood from the following description taken in connection with the accompanying drawings, and the novel features thereof are pointed out and clearly defined in the claims at the 45 close of the specification.

In the drawings,—Figure 1 is a front view of a card embodying my invention. Fig. 2 is a back view of a card shown in Fig. 1. Fig. 3 is a front view of a card 50 provided upon its face with a set of product numerals and adapted to be used with the card shown in Fig. 1. Fig. 4 is a front view of a card embodying my invention but having the product numerals placed on the

front face of the card adjacent to the spaces 55 to which they apply.

Referring now to Fig. 1—a portion of the card 11 there shown is divided into spaces 12 which are conveniently of equal size and arranged vertically in columns of equal 60 height and horizontally in rows. In one of the columns of said spaces 12 beginning part way up from the bottom are placed numerals 13 indicating the hours of the working day; in this case 8, 9, 10, etc., and 65 above this portion of the space is written the word "In" to indicate that these numerals 13 may be employed to designate the time at which the workman begins work. These numerals 13 are for convenience called 70 the subtrahend numerals. Opposite to and in the same line of spaces with each of said subtrahend numerals 13 is located a second set of numerals, the said sets being designated 14, 15, 16, 17, 18, 19, 20 and 21 respectively. 75 These sets of numerals are called the minuend numerals and each set corresponds to the hours of the working day which come after the hour indicated by the numeral of the subtrahend numerals with 80 which they correspond. Thus, the set 14 begins at 9, that being the first hour after the hour 8 which is indicated by the numeral 8 of the subtrahend numerals 13. Similarly the set 15 begins at 10, that being the hour 85 next after the hour indicated by the numeral in the column of subtrahend numerals, etc. The minuend numerals have placed above them the word "Out", and these numerals indicate the time at which the workman leaves the job. It will be seen that by punching the subtrahend numeral and one 90 of the minuend numerals the time when the workman enters and leaves the factory or job will be recorded on the face of the card. 95 The face of the card may also contain spaces for such other information as desired. In practice I find it convenient to provide the names of the months as shown at 22 and a set of numerals indicating the days of the 100 month as shown at 23, so that the month and day may be punched; also the number of the workman's card. Other spaces may be provided to contain such other information as may be necessary or convenient. Additional 105 directions for punching may also be provided if desired.

The back of the card is ruled off into

2

spaces corresponding with the numbered spaces on the front of the card, and these spaces register with the spaces on the front of the card. To each of the spaces on the back of the card which register with a space occupied by one of the minuend numerals on the front of the card is applied a numeral which for convenience I call a product numeral. This numeral may be in the space registering with the corresponding space on the front of the card or may be in a space next adjacent to it, the latter method being preferred and employed by me in practice because the product numeral is then not obliterated when the minuend numeral on the front of the card is punched. These product numerals are designated 24 in Fig. 2 and each of them is equal to the difference between the minuend numeral 20 and its corresponding subtrahend numeral multiplied by a constant which is the wage per hour. Thus, the numeral 29 (see Fig. 2) of the product numerals is equal to the difference in hours between the subtrahend 25 numeral (see Fig. 1) which was obliterated by the punch mark 27 and the minuend numeral (see Fig. 1) which was obliterated by the punch mark 28, multiplied by the rate per hour which was \$10. The card 30 then shows that the workman has worked the six hours from nine until four with the exception of the noon hour and has earned \$60, but no figuring has been required to attain this result.

35 In Fig. 3 is shown a second card 25 provided with spaces 26 arranged similarly to those shown in Figs. 1 and 2, but it will be seen that the order and position of the numerals is exactly reversed from that shown in Fig. 2 in order that when the cards shown in Figs. 1 and 3 are superposed, the numerals will correspond. Such other information may be placed upon the card shown in Fig. 3 as may be desired.

45 In Fig. 4, there is shown a card 30 in which the product numerals 31 are placed in spaces adjacent to or a part of the spaces which are occupied by the minuend numerals 32, the subtrahend numerals being shown 50 at 33. In this way, all the figures are upon one side of the card which may be more convenient than to have them on two cards or on opposite faces of the same card.

The operation of my improved account- 55 ing system is as follows:—When the workman arrives at his work, he receives from the time-keeper or boss a card like that shown in Figs. 1 and 2 or a pair of cards, one of which (25) is like that shown in Fig.

60 3. The time-keeper punches the hour when the workman arrives in the column of subtrahend numerals. When the workman has completed his work, he goes again to the boss or time-keeper with his card or cards 65 and the time-keeper punches the minuend

numeral indicating the time at which the card is presented, this minuend numeral being that one which is in the line of minuend numerals, the subtrahend numeral of which was punched to show the time when the workman came in. In the drawings, the card of Fig. 1 is shown as punched at 27 indicating that the workman began work at 9 o'clock and at 28 in the set 15 of minuend numerals showing that the workman left 75 at 4 o'clock. Upon turning the card over, it will be seen, see Fig. 2, that the man has earned \$60, that being the product numeral in the space next above the punch mark 28. This card bears the instructions "Read 80 above the punch mark" as the product numerals are placed in the space above those to which they apply, so that they are not obliterated by the punch mark. The other card 25 of the pair shows that the man arrived at 9 o'clock and earned \$60.

The workman receives the card shown in Fig. 1 as his voucher for his pay, and the card shown in Fig. 3 goes to the cashier who makes up his pay roll from it, receiving 90 from the workman the workman's card in exchange for the money.

It will be seen that no mental labor or calculation whatsoever is required after the cards have been punched, and that there is 95 no more mental effort required to punch the cards than heretofore to punch cards indicating the hours at which the workman arrives and leaves from which the time worked is calculated and afterward multiplied by the price per hour.

I claim as my invention:

1. The improved card for an accounting system marked off into spaces of equal size arranged in columns vertically and in rows 105 horizontally and provided in one of said columns with a set of numerals forming a series, said card or slip having also other sets of numerals, one set for each numeral of said series and arranged in the same row 110 therewith, and a third set of numerals each of which is so located with relation to the numerals of the said second mentioned set that a single punch mark will indicate a numeral of the third set and a numeral of 115 the second set.

2. The improved card for an accounting system marked off into spaces of equal size arranged in columns vertically and in rows 120 horizontally and provided in one of said columns with a set of numerals forming a series, said card having also other sets of numerals, one set for each numeral of said series and arranged in the same row therewith, each of said last mentioned sets of numerals forming that part of the series of the first mentioned set which begins with the number of the series next higher than the number of the first set of numerals, and 130 a third set of numerals each of which is so 1

- located with relation to the numerals of the second mentioned set that a single punch mark will indicate a numeral of the third set and a numeral of the second set.
5. 3. The improved card or slip for an accounting system having its front and back faces marked off into spaces of equal size arranged in columns vertically and in rows horizontally, said spaces on the front and back faces registering with each other, said card or slip being provided in one of the columns of spaces on the front face with a set of numerals forming a series, other sets of numerals, one set for each numeral of said series and arranged in the same row therewith, and upon its back face with a third set of numerals, each of which is in register with one of the figures of the second mentioned set.
10. 10. 4. The improved card or slip for an accounting system having its front and back faces marked off into spaces of equal size arranged in columns vertically and in rows horizontally, said spaces on the front and back faces registering with each other, said card or slip being provided in one of the columns of spaces on the front face with a set of numerals, also with other sets of numerals, one set for each numeral of said first mentioned set and arranged in the same row therewith, and upon its back face with a third set of numerals, each of which is in register with one of the figures of the second mentioned set.
15. 20. 5. The improved card or slip for an accounting system marked off into spaces of equal size arranged in columns vertically and in rows horizontally and provided in one of said columns with a set of numerals indicating the hours of the working day, other sets of numerals one set for each numeral of the first mentioned set arranged in the same row therewith and beginning with the hour next above that indicated by said numeral of the first mentioned set, and a third set of numerals each of which is so located with relation to the numerals of the said second mentioned set that a single punch mark will indicate a numeral of the third set and a numeral of the second set, the numerals of said third mentioned set when divided by a constant which is the wage per hour being the difference in hours between the hour indicated by the numeral of the first mentioned set and the hour indicated by the numeral of the second mentioned set.
25. 30. 6. The improved card or slip for an accounting system having its front and back faces marked off into spaces of equal size arranged in columns vertically and in rows horizontally, said spaces on the front and back faces registering with each other, said card or slip being provided in one of the columns of spaces on the front face with a set of numerals indicating the hours of the working day, and also having on its front face other sets of numerals, one set for each numeral of the first mentioned set arranged in the same row therewith and beginning with the hour next above that indicated by said numeral of the first mentioned set, said card being provided upon its back face with a third set of numerals, each of which is in register with one of the figures of the second mentioned set and is, when divided by a constant which is the wage per hour, the difference in hours between the hour indicated by its said registering numeral of the second mentioned set and the hour indicated by the numeral of the first mentioned set in whose row it is.
35. 40. 7. The improved card or slip for an accounting system having its front and back faces marked off into spaces of equal size arranged in columns vertically and in rows horizontally, said spaces on the front and back faces registering with each other, said card or slip being provided in one of the columns of spaces on the front face with a set of numerals forming a series, other sets of numerals, one set for each numeral of said series and arranged in the same row therewith, and upon its back face with a third set of numerals, each of which is in register with one of the figures of the second mentioned set.
45. 50. 8. The improved card or slip for an accounting system having its front and back faces marked off into spaces of equal size arranged in columns vertically and in rows horizontally, said spaces on the front and back faces registering with each other, said card or slip being provided in one of the columns of spaces on the front face with a set of numerals forming a series, other sets of numerals, one set for each numeral of said series and arranged in the same row therewith, and upon its back face with a third set of numerals, each of which is in register with one of the figures of the second mentioned set.
55. 60. 9. The improved card or slip for an accounting system having its front and back faces marked off into spaces of equal size arranged in columns vertically and in rows horizontally, said spaces on the front and back faces registering with each other, said card or slip being provided in one of the columns of spaces on the front face with a set of numerals indicating the hours of the working day, and also having on its front face other sets of numerals, one set for each numeral of the first mentioned set arranged in the same row therewith and beginning with the hour next above that indicated by said numeral of the first mentioned set, said card being provided upon its back face with a third set of numerals, each of which is in register with one of the figures of the second mentioned set and is, when divided by a constant which is the wage per hour, the difference in hours between the hour indicated by its said registering numeral of the second mentioned set and the hour indicated by the numeral of the first mentioned set in whose row it is.
65. 70. 10. The improved card or slip for an accounting system having its front and back faces marked off into spaces of equal size arranged in columns vertically and in rows horizontally, said spaces on the front and back faces registering with each other, said card or slip being provided in one of the columns of spaces on the front face with a set of numerals indicating the hours of the working day, and also having on its front face other sets of numerals, one set for each numeral of the first mentioned set arranged in the same row therewith and beginning with the hour next above that indicated by said numeral of the first mentioned set, said card being provided upon its back face with a third set of numerals, each of which is in register with one of the figures of the second mentioned set and is, when divided by a constant which is the wage per hour, the difference in hours between the hour indicated by its said registering numeral of the second mentioned set and the hour indicated by the numeral of the first mentioned set in whose row it is.
75. 80. 11. The improved card or slip for an accounting system having its front and back faces marked off into spaces of equal size arranged in columns vertically and in rows horizontally, said spaces on the front and back faces registering with each other, said card or slip being provided in one of the columns of spaces on the front face with a set of numerals forming a series, other sets of numerals, one set for each numeral of said series and arranged in the same row therewith, and upon its back face with a third set of numerals, each of which is in register with one of the figures of the second mentioned set.
85. 90. 12. The improved card or slip for an accounting system having its front and back faces marked off into spaces of equal size arranged in columns vertically and in rows horizontally, said spaces on the front and back faces registering with each other, said card or slip being provided in one of the columns of spaces on the front face with a set of numerals forming a series, other sets of numerals, one set for each numeral of said series and arranged in the same row therewith, and upon its back face with a third set of numerals, each of which is in register with one of the figures of the second mentioned set.

In testimony whereof I affix my signature, in presence of two witnesses.

EDWARD C. ALBREE.
